UNITED STATES PATENT OFFICE.

JOSEPH EPSTEIN, OF BROOKLYN, NEW YORK.

BEDSPRING.

Application filed April 10, 1925, Serial No. 22,030.

In the manufacture of wire fabrics used for the bottoms of beds, couches, and the like articles of furniture, the controlling requirements are two-fold: the wire fabric must be 5 inextensible, that is, will not sag when the weight is removed, and yet at the same time must be flexible in all directions. A wire fabric having these properties or characteristics must also be so constructed that it 10 can be produced at a cost to meet the competition of inferior fabrics. The object of the present invention is to produce an improved wire fabric for beds, couches, and the like, the parts of which are so formed 15 and arranged that the fabric possesses the required flexibility in all directions, does not sag when the superimposed weight is removed, can be readily folded longitudinally and transversely, if that is desired, 20 and can be manufactured at a saving in cost of production and of material. To the accomplishment of this object the invention consists in the improved wire fabric hereinafter described and particularly 25 pointed out in the appended claims.

The preferred form of the invention is illustrated in the accompanying drawings in which:

Fig. 1 is a plan of a bed or couch bottom 30 employing the improved wire fabric;

Fig. 2 is an enlarged perspective view of one of the main links of the fabric;

Fig. 3 is a view similar to Fig. 2 of one 35 of the auxiliary side links;

Fig. 4 is a detail of one form of coupling link; and

Fig. 5 is a similar view of another form 40 of coupling link.

In the illustrated embodiment of the invention, the improved wire fabric is shown attached to a bed or couch frame of which the longitudinal side members are indicated at 7 and the end pieces at 8. The wire fabric comprises a series of lateral rows of 45 main links 9 which are held in cooperative relationship by means of the intermediate or coupling links 10. Each main link 9 consists of a strand of wire bent upon itself, as shown in Fig. 2, with its two side or limb sections 11 and 12 extending parallel with each other, the inner ends of the limbs being connected by the curved transverse member 13. By bending the transverse member 13 inward with respect to the side 50 links 11 and 12, the pockets or notches 14 are formed, and these pockets are adapted

to receive and hold in place the hook portions 15 of the coupling links 10. The free ends 17 of the limbs 11 and 12 are bent under to form long, relatively flat hooks. 60

The hooks 17 of the first lateral row of links are adapted to engage the series of helical springs 18 connected with one of the end pieces 8 of the bed or couch frame. The hooks 17 of the remaining rows of links are 65 adapted to engage the loop portions 19 of the coupling links 10. The last row 20 of coupling links 10 are adapted to engage the series of helical springs 21 connected with the other end piece 8 of the bed or couch 70 frame.

When the main links 9 and intermediate or coupling links 10 are assembled together to constitute the improved wire fabric shown in Fig. 1, the limbs 11 of each longitudinal row of links are arranged relatively close to and substantially parallel with the limbs 12 of the adjacent longitudinal row of links. This mode of arrangement provides 75 a series of longitudinally extending link sections each composed of two closely positioned limbs, although the limbs of the individual links are spaced relatively far apart. The proper lateral spacing between the limb 11 of one link 9 and the limb 12 of the 80 adjacent link 9 is secured by bending the hooks 17 of each individual link 9 slightly outwardly, as shown clearly in Fig. 2, and by spacing the hook portions 15 of the coupling links 10 accordingly. The divergent 85 or angular directions of the sides of the hooks 17 of each individual link 9 result in a convergent relationship of the hooks of the adjacent links when the latter are arranged side by side, as shown in Fig. 1. 90 This convergence of the hooks 17 of the limbs 11 and 12 of adjacent links not only serves to aid in properly spacing and holding apart the limbs of the adjacent links, but also affords the hooks a better purchase or 95 hold in the loops of the helical springs 18 and in the loops 19 of the coupling links 10. 100

The coupling links 10 are so shaped as to cooperate with the limbs 11 and 12 of the adjacent longitudinal rows of links 9 105 to form substantially continuous lineal strands of wire so that the longitudinal stresses imposed on the fabric will be taken up by these double strands of wire in such manner as not to affect the flexibility of 110 the fabric. By flexibility is meant that quality or characteristic which causes the

fabric to yield (in cooperation with the helical springs) when a weight is superimposed upon it, and which causes the fabric to return to original position without sagging when the superimposed weight is removed. The coupling links may be substantially U-shaped, as shown in Fig. 4, or substantially V-shaped, as shown in Fig. 5. It is preferred, however, to employ the 10 U-shaped links, partly because of considerations of production and its effect on the metal, and partly because with this form of coupling link the sides thereof are more nearly in a straight line with the sides or 15 limbs of the main links 9.

The angular distance between the hooks 15 of the coupling links will depend upon the desired spacing between the limbs 11 and 12 of adjacent links 9. One hook 15 20 of a link 10 is adapted to be received in a pocket 14 of a link 9 and the other hook 15 of the link 10 is adapted to be received in the nearer pocket 14 of the adjacent link 9. The loops 19 of each row of coupling 25 links (except the last) receive the converging hooks 17 of adjacent links 9. The loops 19 of the last row of coupling links receive the hooked inner ends of the helical springs 21. The convex middle portion of each 30 transverse member or piece 13 connecting the limbs 11 and 12 together, serves to keep the hooks 15 in the pockets 14 and to return them thereto when displaced therefrom.

By constructing and arranging the parts 35 of a wire fabric as described above, the separate transverse links or strands of wires heretofore commonly used to connect the longitudinal links together are eliminated, the curved transverse members 13 of the 40 longitudinal links serving in cooperation with the coupling links 10 to absorb the lateral stresses imposed upon the fabric. The present arrangement makes for a strong, durable, and inextensible structure.

In order to provide the side edges of 45 the fabric with double strands of wire, and at the same time have as smooth a side edge as is possible, use is made of auxiliary side links composed of a single strand of wire. 50 These side or auxiliary links 23 serve the two-fold function of the main links and the coupling links. For this purpose the limb section 24 of each one of the left-hand longitudinal links 23 (viewing Fig. 1) 55 cooperates with the limb section 11 of each one of the longitudinal row of main links 9, and the limb section 24 of each one of the right-hand longitudinal row of links 23 cooperates with the limb section 12 of 60 each one of the adjacent longitudinal row of main links. The loop portion 25 of the auxiliary links 23 performs the function of

the coupling links in that the hook 26 of each link 23 is received in the nearer pocket 14 of the adjacent main link, and the hook end 27 of each link 23 is received in the loop 25 of the preceding link 23, in which loop is also received the loop 17 of the limb 11 or 12 of the adjacent main link.

What I claim as my invention and desire 70 to secure by Letters-Patent, is:

1. A wire fabric for beds and the like comprising a series of lateral rows of longitudinally extending main links, each main link consisting of a pair of parallel limbs 75 connected at one end by a curved transverse member which forms a pocket with each limb, the free ends of the limbs being hook-shaped and diverging from each other, a series of lateral rows of coupling links, each 80 coupling link having its free ends hook-shaped for engagement in the nearer pockets of two adjacent main links, the middle portion of each coupling link being formed as a loop for the reception of the convergent 85 hooks of adjacent main links, and a series of single strand auxiliary links arranged at each side of the fabric, each auxiliary link being connected with an adjacent main link and having a loop adapted to receive a 90 hook of an adjacent main link and a hook of the next succeeding auxiliary link.

2. A wire fabric for beds and the like comprising a series of lateral rows of main links, a series of lateral rows of coupling links, and two longitudinal series of auxiliary links, all of said links interengaging and cooperating to constitute the fabric, each main link consisting of two substantially parallel limbs connected by a curved 95 transverse member forming a pocket with each limb, the free ends of the limbs being offset to diverge from each other and provided with hooks, each coupling link 100 consisting of a loop and two hooks, the hooks of the coupling link being adapted to be received in the nearer pockets of two adjacent main links and the loop portion of each coupling link being adapted to receive the two nearer hooks of succeeding adjacent main links, and each auxiliary link 105 consisting of a single strand limb having a hook at one end and an offset loop and a hook at the other end, the loop being adapted to receive a hook of an adjacent main link and a hook of the next succeeding auxiliary link, and the hook at the looped portion of the auxiliary link being adapted to be received in the free pocket of an adjacent main link.

In testimony whereof I hereunto affix my signature.

JOSEPH EPSTEIN.
